UNITED STATES PATENT OFFICE

2,581,121

MEANS FOR CHANGING BAFFLE PITCH IN A
HEAT EXCHANGERWilliam N. McCurdy, Jr., Elizabeth, and John V.
Whittlesey, Roselle, N. J., assignors to Standard
Oil Development Company, a corporation of
Delaware

Application December 23, 1947, Serial No. 793,428

2 Claims. (Cl. 257—239)

1

The present invention relates to an improved heat exchanger structure, and more particularly to an improvement in means for positioning and holding baffle elements therein in combination with means for protecting a heat exchanger tube bundle from accidental damage during insertion in or removal from an exchanger shell. A special feature of the invention is the provision of such means while also providing a means whereby the baffle "pitch," that is, the distance between individual baffles associated with the bundle may be altered without removing the tubes from their connection to either or both fixed and floating tube sheets.

In the conventional heat exchanger tube bundle, the exchanger tubes are mounted in one or the other of the tube sheets, preferably the fixed sheet, the tubes being passed through perforations in the several baffle members used. At the same time, tie rods are inserted through certain of the perforations of the baffle members, usually around the perimeter, passing through tubular spacer elements disposed between the baffle members, which are of such length as has been determined as suitable for the spacing of such members, the tie rod being secured at one end to the fixed tube sheet and at the other to the last baffle member in the bundle. The tubes are then secured to the floating tube sheet.

In a tube bundle assembled in this fashion, it is frequently impossible to vary the pitch or spacing of the baffle members without completely removing the floating tube sheet or head, and also partially or fully withdrawing the tie rods for replacement of the spacer elements. Such an operation is extensive in nature and rather costly in time.

The present invention provides the means whereby baffle pitch may be varied easily, and with a minimum expenditure of time. Such means may be more clearly understood from the following description when read in conjunction with the accompanying drawings, in which:

Fig. 1 is a perspective view of a heat exchanger with the shell and a portion of the tube bundle partly broken away to show the relationship of the several elements.

Fig. 2 is a vertical, longitudinal section through a tube bundle assembled with slotted strip elements spacing and holding the baffle members therein.

Fig. 3 is a perspective view of a baffle holding slotted strip element.

Fig. 4 is a cross-sectional view along the line

IV—IV of Fig. 1 showing the location and disposition of associated elements of the assembly.

Referring now to the several figures with more particularity, similar elements of the structure being indicated by the same numerals as in Fig. 1, the numeral 1 designates an exchanger shell in which is disposed an exchanger tube bundle. Primarily, the bundle is composed of fixed and floating tube sheets 2 and 3 respectively secured therein, a plurality of tubes 4, a plurality of baffle members 5, tie rods 6, spacer elements 7, and tube protector or cage rods 8 which serve to enclose the bundle in a protective cage of substantially rigid solid bars. These tube protectors or cage rods 8 are disposed in the peripheral space between the outer edge portions of the several baffle members, and the periphery of the tube bundle, as shown, extending from a point of attachment on one tube sheet, through the several baffle members, into unsecured, spaced relation to the other tube sheet. The rods 8 are intended to be of substantially the same diameter as the tubes, and disposed so as to conform with the arrangement pattern of the tubes in the bundle. It is also desirable that where possible, the positioning-retainer members, such as rods 6 and elements 7, also conform to the tube arrangement in the tube bundle. The relative location of these elements is still more clearly illustrated by the showing of Fig. 4, which also shows the baffle member construction by which a primary object of the invention is achieved. As indicated, each baffle is provided with a plurality of slots 5a disposed in any desired spaced relation peripherally of the members 5. These slots are adapted to receive the baffle retaining members, such as tie rods 6. By this means, the tie rods 6 may be lifted out of the respective slots 5a in baffles 5, by merely separating the rod from its connection to the last baffle and to the fixed tube sheet. When thus removed, the baffle members may be shifted along the tubes and protector bars so as to alter their spacing in any desired fashion. After replacing or shifting the spacer elements 7 to suit the new spacing arrangement, or baffle pitch, the tie rods may be replaced in the slots 5a and the assembly restored to service. Also cleaning of the tube bundle exteriorly is facilitated by provision of the readily moveable tie rods and baffle members described. In addition, by providing for adjustment of baffle location, in the manner set forth, it is possible to avoid localized erosion of tubes and the shell caused by higher velocity flow of liquid through the clearance space between the tubes and the baffle perforations therefor, and be-

between the peripheral edges of the baffles and the shell. The cage rods 8, in addition to providing substantial protection for the tube bundle, also serve to fill the peripheral space between the edges of baffles 5 and the periphery of the tube bundle, which space in the conventional tube bundle permits annular bypassing of the bundle between baffles by the preferential flow of liquid, gas or vapor through such space. The rods 8 by at least partially filling this annular space prevents partial channeling of flow through the exchanger between baffles.

In Figs. 2 and 3, a form of construction is illustrated, in which the means for positioning and holding the baffle members 5 is a strip member 9, slotted as at 9a in any desired fashion, but preferably so as to provide a maximum number of slots while avoiding excessive weakening of the strip. The strip 9 is inserted in the slots 5a of the baffle member 5 so that the bottom or inner ends of slots 9a engage the same portion of slots 5a, the depth of the respective slots being such that when so inserted the outer edge portions of the strips will coincide and be in the same plane with the edge portion of the respective baffle members. Each strip is provided with a lug portion 9b by which it is secured to the fixed tube sheet. The other end of each strip member is held in place by means of engagement of the slotted portions 5a and 9a, and by a retaining ring 10 which encircles the bundle over the strips 9. Additional rings 10 may be utilized, and disposed at spaced intervals longitudinally of the bundle, if desired. When baffle positioning and retaining strip members 9 are employed the annular, channeled flow of fluid between baffles is also impeded, and this result is still further improved by the use of strip members 9 in conjunction with the rods 8.

The useful benefit of the invention is obtained in this form of the invention by removing the ring members 10, and detaching the lugs 9b from the fixed tube sheet 2, after which the strips 9 may be lifted out of slotted engagement with the baffle members 5. The baffles 5 may then be redisposed as desired and as permitted by the arrangement and spacing of slots 9a, and the assembly restored. Provision is made for maintaining a reserve supply of baffle members or for removal of baffles from operative use by providing a series of closely spaced slots adjacent the fixed tube sheets. Where it is desired to remove baffles from operation, they may be shifted to that end of the bundle, and held there, while the remaining baffles are redisposed. Where the

tie rods 6 and spacer elements 7 are utilized, the same result may be accomplished by use of spacer elements of suitable length between the outer stored baffle and the next adjacent operating baffle.

The invention has been described in conjunction with the accompanying drawings for the purpose of illustration, and it is not intended that the invention shall be thus limited, but only by the appended claims.

What is claimed is:

1. In a heat exchanger, including an exchanger tube bundle having a fixed tube sheet, a floating tube sheet, and a plurality of exchanger tubes 15 connecting said sheets, adjustable baffle means for said tube bundle, comprising a plurality of perforated lateral baffle members disposed in spaced relation longitudinally of said bundle with the exchanger tubes passing through said perforations, said members being slideable along said tubes, slotted portions in spaced relation peripherally of said members and aligned from member to member, a plurality of strip-like spacer-retainer elements each having lateral slotted portions extending into one edge thereof, said slotted portions adapted to engage the slotted portions of said baffle members with the outer edge of said strip-like elements level with the edges of said members, said element secured 30 at one end to the fixed tube sheet, and at least one annular retainer member encircling the spacer-retainer elements, maintaining said elements in fixed relation to said baffle members.

2. An apparatus according to claim 1, in which 35 the strip-like retainer element is provided with an additional series of slotted portions in the end secured to said fixed tube sheet, which portions are adapted to receive baffle members, while not in service in the tube bundle.
